UNITED STATES PATENT OFFICE.

CORNELIUS TENNEY, OF BROOKLYN, NEW YORK, ASSIGNOR TO THE C. TENNEY HARDWARE COMPANY, OF SAME PLACE.

ROD FOR SAW-FRAMES.

SPECIFICATION forming part of Letters Patent No. 310,866, dated January 13, 1885.

Application filed July 8, 1884. (No model.)

To all whom it may concern:

Be it known that I, CORNELIUS TENNEY, a citizen of the United States, residing at Brooklyn, in the county of Kings and State of New York, have invented certain new and useful Improvements in Rods for Saw-Frames, of which the following is a specification, reference being had therein to the accompanying drawings.

10 My invention relates to improvements in tension-rods for saws, and has for its object to lessen the number of parts of which said rods are usually composed, to secure greater strength and durability, and simplify and cheapen their manufacture.

15 The invention consists of the combination and arrangement of parts, substantially as hereinafter fully described and claimed.

In the drawings, Figure 1 represents a finished tension-rod embodying my improvements in position upon a saw-frame. Figs. 2 to 7, inclusive, represent the rod-blank at different stages of its production.

20 Similar letters of reference in the several drawings denote like or corresponding parts.

25 Referring to the drawings, A designates the rod, consisting of the two parts B B', provided at their adjacent ends *b b'* with male screw-threads; and B², an interposed link having its ends provided with female screws, whereby the link can be turned upon the parts B B' to increase the tension of the latter. Each of the rods B B' consists of a single piece of wire (see Fig. 2) which is bent at its middle, as shown in Fig. 3, and at its points *n*, (see Fig. 4,) to form loops N, that encircle the upper ends of the saw-frame, and of straight parts *m m*, which are twisted together, as shown in Fig. 5, and

have their ends welded together and provided with male screw-threads, as shown in Figs. 6 and 7. It will be seen that the parts B B' have great rigidity, strength, and durability, as well as neatness in appearance and simplicity in form. If desired, the welded ends *b b'*, having the screw-threads, may be made of larger diameter than the combined diameter of the folded wire by welding said ends together with a strip of metal, and then finishing said ends with screw-threads. If desired, the twist of the parts B B' may be in opposite directions, so that when said parts are applied to the frame the turning of the central link, B², to increase the tension of the rod will be in the direction of the twist.

20 I am aware that it is not new to make the body or shank of a bolt of a number of wires so twisted together as to give the bolt a certain degree of elasticity to avoid the injurious effects caused by heavy projectiles striking the plate.

Having thus fully described my invention, what I claim, and desire to secure by Letters Patent of the United States, is—

25 A tension-rod for saws, made of wire, each part folded upon itself and its ends twisted together, forming a loop, and welded and threaded, in combination with an intermediate threaded tension-link, as herein shown and described.

In testimony whereof I affix my signature in presence of two witnesses.

CORNELIUS TENNEY.
